LINOLEUM RUG

John R. Quigley, Youngstown, Ohio

Application March 1, 1954, Serial No. 29,265

Term of patent 14 years

(Cl. D34—5)

To all whom it may concern:

Be it known that I, John R. Quigley, a citizen of the United States, residing at Youngstown, in the county of Mahoning and State of Ohio, have invented a new, original, and ornamental Design for a Linoleum Rug, of which the following is a specification, reference being had to the accompanying drawing, forming a part thereof.

Figure 1 is a plan view of a linoleum rug, showing my new design.

Figure 2 is a perspective view of the linoleum rug partly unrolled.

The characteristic features of applicant's design reside in the portions shown in full lines.

I claim:

The ornamental design for a linoleum rug, as shown and described.
